UNITED STATES PATENT OFFICE

154,960

DESIGN FOR AN ELECTRIC LIGHTING FIXTURE

Martin W. Schwartz and Max J. Marks,
Chicago, Ill.

Application July 1, 1946, Serial No. 131,247

Term of patent 3½ years

(Cl. D48—4)

To all whom it may concern:

Be it known that we, Martin W. Schwartz and Max J. Marks, citizens of the United States and residents of Chicago, in the county of Cook and State of Illinois, have invented a new, original, and ornamental Design for an Electric Lighting Fixture, of which the following is a specification, reference being had to the accompanying drawing, forming a part thereof.

In the drawing,

Figure 1 is a perspective view of an electric lighting fixture showing our new design as taken from one side thereof intermediate the ends.

Fig. 2 is an end view of the upper end of the fixture shown in Fig. 1; and

Fig. 3 is an end view of the lower end of the fixture as shown in Fig. 1.

We claim:

The ornamental design for an electric lighting fixture, as shown.

MARTIN W. SCHWARTZ.
MAX J. MARKS.
